CONTROLLER FOR ELECTRIC MOTOR-
DRIVEN TRAVELING DEVICES

Eivind U. Lassen, Whitefish Bay, Wis., assignor
to Cutler-Hammer, Inc., Milwaukee, Wis., a
corporation of Delaware

Substituted for application Serial No. 498,537,
August 13, 1943. This application August 12,
1944, Serial No. 549,258

20 Claims. (Cl. 187—29)

1

The present invention relates to control for electric motor driven traveling devices and is particularly applicable to and advantageous for control of elevators and other traveling devices.

The present application more particularly relates to modifications of the system disclosed in the Seeger Patent 2,368,333, filed June 17, 1943, and is a substitute for applicant's prior application, Serial No. 498,537, filed August 13, 1943, and since abandoned, for Controllers for motor driven traveling devices; Cutler-Hammer, Inc., of Milwaukee, Wisconsin, being the assignee of both applications.

Where it is desired to start and stop traveling devices, such as elevators, from various landings as by push button switches with registration of a plurality of calls for automatic stopping of the elevator car at the landings, the calls are set up in such a manner that the traveling device stops in succession at the various landings for which push buttons have been operated in the natural order of such landings. This requires that the traveling device completes its travel in a given direction before it reverses to respond to push buttons which have been operated calling upon the car to travel in the opposite direction. It has been found necessary heretofore to provide costly and complicated means and circuits to effect the desired automatic starting and stopping.

The present invention has among its objects to provide suitable control for elevators and other traveling devices affording the aforesubdiscussed and other features with simplification of the control apparatus and of the control circuits.

Another object is to provide a control system of the aforesubdiscussed character which requires a minimum of electromagnetic switching apparatus.

Another object is to provide a system which employs a control panel containing the electromagnetic control devices the assembly and wiring of which is independent of the number of floors served.

Another object is to provide a control system in which electric energy is stored up as an incident to actuation of a push button switch for starting and for registering a call at a given landing, and in which the stored energy is discharged upon entry of the device into a given zone of travel from a given direction, to effect stoppage of the device.

Another object is to provide a control system including electromagnetic means which are energized to start the device and including means for storing up energy upon registering a call and

2

discharging said stored energy to ultimately de-energize said electromagnetic means for stopping upon the device approaching the desired landing in the desired direction.

Other objects and advantages will appear from the following description and claims.

The accompanying drawing is illustrative of a system embodying the invention.

In the drawing,

10 Figure 1 is a general representation of an elevator installation including the elevator car with its driving motor and their general relation to the several elements of the control system.

Fig. 2 is a circuit diagram of the control circuits of the system, and

Fig. 3 is a chart of the electromagnetic switches and relays of Fig. 2, said chart having the co-ordinated windings and contacts horizontally aligned with the corresponding elements in Fig. 2.

20 Referring to Fig. 1 of the drawings, the same illustrates an elevator for four floors having a car 1 which is operated by a reversible direct current shunt wound motor 2, the latter having an armature 2^a and a shunt field winding 2^b. The motor and the control circuits are supplied with energy from the direct current lines L¹, L².

The energy supplied to the motor is controlled through an electromagnetic main switch 24 and a pair of electromagnetic reversing switches 4

30 and 5. The main switch 24 is provided with an energizing winding 24^a, normally open main contacts 24^b, and as shown in Fig. 3 normally open auxiliary contacts 24^c, 24^e and a delayed action normally open contact 24^d.

The electromagnetic switch 4 is designed to effect operation of the elevator in an upward direction and is provided with an energizing winding 4^a, normally open main contacts 4^b and 4^c, and as shown in Fig. 3 with normally open auxiliary contacts 4^d, 4^e, 4^g and 4^h, and normally closed auxiliary contacts 4^f.

The electromagnetic switch 5 effects operation of the elevator in a downward direction and is provided with an energizing winding 5^a, normally open main contacts 5^b and 5^c, and as shown in Fig. 3 with normally open auxiliary contacts 5^d, 5^f, 5^g and 5^h, and normally closed auxiliary contacts 5^e.

The elevator car is connected with the motor armature by means of ropes or cables connected to a pulley 3 which is mounted on the motor shaft. Also mounted on the motor shaft is an electromagnetic brake 32, having an energizing winding 32^a, which when energized releases the brake.

Also connected to the car by means of a rope and counterweight so as to move in synchronism with

the car is a sheave wheel 7. On its shaft is mounted a rotating floor selector 8 having two substantially semicircular contact segments 8^a and 8^b, which are insulated from one another. The sheave 7 is arranged so that the floor selector makes substantially one-half revolution during the travel of the elevator car from the lowest to the highest limit. The segments 8^a and 8^b are provided with contact brushes 8^c and 8^d. Each of said brushes is at all times in engagement with one of the segments to conduct current thereto. Additional contact brushes 8^e to 8^h, inclusive, corresponding in number to the number of floors, are arranged about the left-hand portion of the circumference of selector 8 between the brushes 8^a and 8^b to make contact with one or the other of the segments 8^a, 8^b, depending upon the position of the car in the hatchway. The sheave 7 also drives traveling nut selector switches 9, 10 and 11. The selector switch 9 has a bridging contact 9^a, which makes contact with a contact segment 9^b and with contact buttons 9^c to 9^f, selectively. Each of the contact buttons 9^c to 9^f corresponds to one of the floors of the elevator. Similarly the selector switches 10 and 11 are provided with bridging contacts 10^a and 11^a, respectively, contact segments 10^b, 11^b, respectively, and contact buttons 10^c to 10^f, and 11^c to 11^f, respectively.

Mounted at the various floors are push button stations 12 to 15, inclusive, adapted to initiate starting of the elevator. The push button stations 12 and 15 are mounted at the first and last floors, respectively, and are single push button stations provided with triple normally open contacts. The push button stations 13 and 14 mounted at the second and third floors, respectively, are each provided with two triple contact normally open push button switches, one push button switch of each pair being operable for stopping on downward movement and the other being operable for stopping on upward movement of the car, and each providing for starting of the car when at rest. Floor hatchway limit switches 16 to 19, inclusive, are mounted in the hatchway, being spaced correspondingly to the spacing of the floors. These hatchway switches are provided with normally closed contacts and are operable to the open position by means of a retiring cam 34, mounted on the car and having an energizing winding 34^a. When the winding 34^a is deenergized the retiring cam moves into a relationship to the limit switches 16 to 19, so as to open each as the car approaches the respective landing and to maintain each open as long as the retiring cam winding is deenergized, and the car is at the respective landing.

There are also installed in the hatchway near the lowermost and uppermost limits of travel, normally open stop limit switches 30 and 31, respectively, operable respectively by cams 30^b and 31^b on the car. Double pole normally closed limit switches 27 and 28 are mounted in the hatchway, being respectively provided with two normally closed contacts 27^a, 27^b, and 28^a, 28^b, these contacts being opened by abutment of the elevator car with the respective limit switch upon arrival of the car at the respective lower and upper limits of travel.

As shown in Figs. 2 and 3 the control panel is further equipped with an "up" relay 25 and a "down" relay 26, having electromagnetic windings 25^a and 26^a, respectively, and normally open contacts 25^b and 25^c, and 26^b and 26^c, respectively. The controller further includes a stop relay 29, having energizing windings 29^a, 29^b and 29^c, and

normally open contacts 29^d, 29^e, and said controller also includes a retiring cam relay 33, having an energizing winding 33^a, normally open contacts 33^b, and normally closed contacts 33^c.

5 Mounted in the elevator car are normally open triple contact push button switches 20 to 23, inclusive, one for each floor.

10 Connected between one contact of each of the push button switches 12 to 15, inclusive, and the line L² is one of a group of condensers 35 to 40, inclusive, while similar condensers 41 and 42 are respectively connected between one contact of the push button switches 21 and 22 and line L². The push button switches 20 and 23 are connected in parallel with push button switches 12 and 15, respectively.

15 To provide for automatic reversal of the elevator under certain conditions, the system further includes two electron tubes 50 and 51 each provided with a cathode 50^a and 51^a, respectively, an anode 50^b and 51^b, respectively, and a control grid 50^c and 51^c, respectively. A resistor 52 is connected between the line L¹ and the cathode 50^a of tube 50, and another resistor 53 is connected between the cathode 50^a and the line L². 20 A resistor 54 has one terminal connected to the grid 50^c and a resistor 55 is connected between the grid 50^c and the line L². The second terminal of the resistor 54 is connected, in series with a condenser 56 of relatively small capacity, to the segment 9^b of the floor selector 9. The cathode 50^a is also connected to the brush 8^c and contacts 25^b, while the anode 50^b is adapted to be connected through contacts 24^e to line L¹. A resistor 57 is connected between the line L¹ and the cathode 51^a of tube 51, and a resistor 58 is connected between the cathode 51^a and the line L². One terminal of a resistor 59 is connected to the control grid 51^c and a resistor 60 is connected between the control grid 51^c and the line L². The second terminal of the resistor 59 is connected, in series with a condenser 61, to the segment 10^b of the floor selector 10. The cathode 51^a is also connected to the brush 8^d and contacts 26^b, while the anode 51^b is adapted to be connected through the contact 24^e to the line L¹. It will be seen that when the tubes 50 and 51 are rendered conducting they afford paths from line L¹, through contact 24^e, to parallel the contacts 25^b and 26^b, respectively.

25 55 For simplicity the usual landing door switches, car door switch and other safety switches have been omitted from the drawing, but it will be understood that the use thereof in the usual manner is contemplated and it may be assumed that such switches are connected in series with the hatchway switches 16 to 19.

30 The system is connected and operates as follows: Let it be assumed that the car is at the first landing and has discharged its passengers from the previous run and let it be further assumed that all of the circuits are deenergized. If now a passenger enters the car and wishes to go to the second floor, he actuates the push button switch 21, which completes a circuit from line L¹, through said push button switch, to the condenser 41 to line L² and the condenser 41 is charged to line potential and stores up electrical energy. A circuit is also completed from line L¹, through the center contact of the push button switch 21 to contact brush 8^f, segment 8^a to contact brush 8^e, through contacts 28^a, through energizing coil 25^a, to line L². Thereupon the relay 25 is energized and it completes a maintaining circuit from line L¹, over contacts 25^b, 28^a and

coil 25^a to line L², so that the relay remains energized when the push button is released. A circuit is also completed from line L¹, through contacts 25^e, 5^e, to and through energizing coil 4^a, contacts 28^b, to line L². This energizes the "up" reversing switch 4 which closes contacts 4^e, paralleling the contacts 25^e and also prepares a circuit (Fig. 1) from line L¹, through contacts 4^b, contacts 24^b, through the armature 2^a, through contacts 4^c to L², but the motor does not start, as switch 24 is still deenergized. Response of switch 4 closes contacts 4^e to establish a circuit from line L¹, through contacts 4^e, 33^c and coil 34^a to line L² to energize the retiring cam and permit closure of limit switch 16. This closes a circuit from contacts 4^e through energizing coil 24^a, through the hatchway limit switches 16, 17, 18, 19 to line L². Thereupon switch 24 responds and closes contacts 24^b to complete the circuit through the motor armature. Contacts 24^c also close and complete a circuit from line L¹, over contacts 4^e, 24^c, to and through energizing coil 32^a to line L². This lifts the brake 32 and the motor operates to move the car in an upward direction. The car now travels upward until the floor limit switches 9, 10, and 11, respectively, bridge the contacts 9^b and 9^d, 10^b and 10^d, and 11^b and 11^d, whereupon a circuit is established from condenser 41 over contacts 11^d, 11^a and 11^b, through energizing coil 29^b, to line L² and back to condenser 41. The energy stored up in the condenser is thereby discharged through the energizing coil 29^b of relay 29, causing the relay 29 to respond. This closes a circuit from line L¹ through contacts 4^e, 29^e, 24^d, energizing coil 33^a, to line L², whereupon the relay 33 responds to open the normally closed contacts 33^c, so that the energizing coil 34^a of the retiring cam is deenergized. Thereupon the retiring cam moves into cooperative relationship to the hatchway limit switch 17 and opens the contacts thereof. This interrupts the energizing circuit of the coil 24^a and the switch 24 disconnects the motor armature from the line and also opens the energizing circuit of the brake coil 32^a by opening contacts 24^c and the brake stops the motor.

Response of relay 33 also closes normally open contacts 33^b, thereby paralleling the contact 29^e of relay 29, so that the relay coil 33^a is maintained energized for a limited time after deenergization of switch 24 by the contact 24^d, thus keeping the retiring cam coil 34^a deenergized and keeping the limit switch 17 open to prevent restarting of the elevator and to permit discharge of the passenger. After a given time determined by the time element of the contacts 24^d, the relay coil 33^a is again deenergized, thereby reclosing contacts 33^c and permitting energization of the retiring cam coil 34^a.

It will be observed that the relay 25 and the reversing switch 4 after they have been closed remain energized until the car reaches its "up" limit, where their energizing circuits are interrupted by opening of the contacts 23^a and 23^b, respectively, the car being stopped at intermediate floors by opening of switch 24 in response to the push button control.

If during the aforesaid travel of the elevator or during its stoppage on the second floor push button 14^b has been depressed the condenser 39 is charged. As soon after stoppage at the second floor as the retiring cam coil 34^a is again energized, the retiring cam is withdrawn and permits closure of limit switch 17, whereupon a circuit is again established from line L¹, through

contact 4^e, through energizing coil 24^a, and the limit switches 16 to 19 to line L². This causes the motor to start again for travel of the car in the upward direction toward the third landing. 5 When the elevator reaches the third landing a circuit is established from the previously charged condenser 39, over contacts 9^e, 9^a, 9^b, through contacts 4^h, relay coil 29^a, to line L². This energizes relay 29 which causes closure of contacts 29^e and stoppage of the elevator in the manner aforescribed.

After discharge of the passenger on the third floor the car continues to travel in the upward direction in the manner aforescribed, until it 15 reaches the uppermost landing, whereupon the contacts 28^a and 28^b of the limit switch 28 open. Opening of the contacts 28^b deenergizes the "up" reversing switch 4 while opening of contacts 28^a opens the energizing circuit of the relay 25 and 20 the elevator will come to a stop.

Just prior to actuation of limit switch 28, the limit switch 31 is closed by the cam 31^b to close a circuit from line L¹, through said switch 31 and contacts 4^d, coil 29^c, the floor limit switches 16 to 19, inclusive, to line L². This causes relay 29 to respond to close contacts 29^d thereby establishing a maintaining circuit for coil 29^c in parallel with the limit switch contacts 31 and contacts 4^d. Response of relay 33 opens the contacts 33^c thereby deenergizing coil 34^a of the retiring cam 34 and said cam 34 causes opening of the contacts 19 and the elevator will remain at the top landing.

If now or previous to the stoppage of the car 35 at the top landing any one of the push button switches, except that for the uppermost floor, is operated, the relay coil 26^a is energized in a manner similar to that described in connection with the relay coil 25^a, when the elevator was 40 assumed to be on the first floor. This circuit extends from line L¹, over the respective push button switch, for instance 13^a or 13^b, brush 8^f, segment 8^b, brush 8^d, contacts 27^a, through relay coil 26^a to line L². This in turn prepares a circuit for 45 energizing the coil 5^a of the "down" reversing switch 5 through a circuit from line L¹, over contacts 26^e, contacts 4^f when engaged, coil 5^a, contacts 27^b to line L², and the controller responds to start the elevator in the downward direction 50 when the "up" switch 4 drops out to reclose contacts 4^f, the relay 26 and the switch 5 performing similar to the relay 25 and the switch 4, but for reverse operation of the motor.

If the elevator is at the top floor and an "up" 55 push button switch on any landing, except the push button switch of the top floor, for instance, the second floor "up" push button switch 13^b, is depressed, a circuit is established from line L¹, through said push button switch 13^b, contact brush 8^f, segment 8^b, brush 8^d, contacts 27^a, relay coil 26^a to line L². The relay 26 closes the contacts 26^b, thereby completing a maintaining connection from line L¹, through contact 26^b to a point adjacent brush 8^d, thence through contacts 60 27^a, through coil 26^a to line L²; thus maintaining the relay 26 energized when the push button is released. A circuit is also established from line L¹, over push button 13^b, to condenser 37, to line L², and the condenser is charged.

70 Response of relay 26 closes contacts 26^e, thereby establishing a circuit from line L¹, through contacts 26^e, contacts 4^f, energizing coil 5^a, contacts 27^b, to line L², and the "down" reversing switch 5 is energized to set up a circuit for the armature 75 to permit the motor to revolve in a downward

direction. Response of the switch 5 opens the contacts 5^e, which prevents the energization of the "up" reversing switch 4. Response of switch 5 further completes a circuit from line L¹, through contacts 5^e, energizing coil 24^a, through the limit switches 16 to 19, inclusive, when all are closed, to line L², and the main switch 24 is energized to complete the armature circuit for reverse operation of the motor to move the elevator car downwardly. Response of the "down" reversing switch 5, with consequent closure of contacts 5^e completes a circuit from line L¹, through contacts 5^g, contacts 33^c, through the retiring cam energizing coil 34^a, to line L², so that the retiring cam 34 is withdrawn and limit switch 19 is closed.

The elevator thus moves in a downward direction until it reaches the second floor, whereupon a circuit is established from the condenser 31, over contacts 9^d, 9^a, 9^b, to the condenser 56, through resistors 54 and 55 to line L² and back to the condenser 31. The condenser 31 thus gives up a small amount of its charge to the condenser 56 and the grid 50^c of the tube 50 is rendered sufficiently positive with respect to the cathode 50^a to make the tube conducting. This completes a circuit from line L¹, through contacts 24^e, tube 50, contacts 28^a, coil 25^a, to line L². Relay 25 is thereby energized and closes its maintaining contacts 25^b. When the elevator reaches the lowest floor and the opening of contacts 27^a deenergizes relay 26, to open contacts 26^b, relay 25 remains energized. However, opening of contacts 27^b opens the maintaining circuit of the "down" reversing switch 5, and the "up" reversing switch 4 is now energized by a circuit from line L¹, through contacts 25^e, contacts 5^e, coil 4^a and contacts 28^b to line L², and the elevator travels in an upward direction as described. If now the elevator reaches the second floor, the condensers 31 and 56 are discharged through the coil 29^a of relay 29 and the relay deenergizes the main switch 24 as aforescribed.

If, while the elevator is traveling upwardly, a "down" button, for instance, the button 14^a, is depressed the relay 26 is energized and the condenser 38 is charged as described. After stopping on the second floor the elevator will proceed to the third floor, and upon reaching the third floor the selector switch 10 will connect the condenser 38 to the condenser 61, and make the tube 51 conducting and thereby pick up relay 26 which will maintain itself through contacts 26^b. Thus upon arriving at the upper limit the relay 25 and the reversing switch 4 are deenergized and the reversing switch 5 is energized to cause the elevator to operate again in a downward direction until the third floor is reached whereupon the condensers 38 and 61 discharge through the energizing coil 29^a to bring the elevator to a stop.

If, while the elevator is moving in a downwardly direction a "down" button is operated at a floor which is above that at which the elevator is at the moment of the operation of the button, the elevator will continue on its downward travel as aforescribed. Thereafter it will reverse at the lower limit, then move upwardly to the upper limit, and again reverse to travel downwardly until it reaches on its second downward travel the floor at which the "down" button has been operated, the operation under these conditions being apparent from the foregoing description.

The foregoing description shows that when while the car is traveling downwardly, following its reversal to answer the first landing call, intermediate landing buttons are operated, the car

will stop at the landings where "down" buttons have been operated and will pass those landings at which "up" buttons have been operated. Then when the car has reached the lowermost landing, it will reverse and answer the calls registered by the "up" buttons, making the stops in both directions in the natural order, regardless of the order in which the buttons have been operated. It is, of course, to be understood that this latter statement presupposes operation of each involved button in time to be effective without repetition of a complete cycle of the car.

On the other hand, the system also provides for repetition of a complete cycle of travel when necessary. For example, if the car has passed the second floor traveling upwardly, when the "up" button at the second floor is operated, said button when operated will initiate maintenance of its call while the car goes to its "up" limit and reverses and then goes to its "down" limit for a second reversal to answer the "up" call at the second floor on the upward travel of the car after said second reversal.

While the system described is provided with a direct current motor, the same may be used for the control of any other type of motor suitable for elevator drive.

The energy for the control circuits may be supplied from an alternating current source through a rectifier. It is also possible to energize only the condensers with direct current and all other circuits with alternating current. In that event, the push button switches must be suitably modified. Other modifications of the system within the scope of the present disclosure and the appended claims will be obvious to those skilled in the art.

I claim:

- 40 1. In control for an electric motor driven traveling device, the combination with means to effect travel of the device through a plurality of zones, said means including a plurality of push button switches, at least one for each zone of travel served by the device and operable to start said device and direct it to the corresponding zone, of separate condenser type energy storing means connected in circuit with said push button switches for charging of the former from an energy source upon operation of said switches, electroresponsive means requiring energization for stopping said traveling device and responsive to discharge of any of said energy storing means, and means responsive to the movement of said traveling device to afford discharge of said separate energy storing means which have been charged, in a predetermined order irrespective of the order of actuation of said push button switches, regardless of any temporary failure of the source of charging current, the first mentioned means including means which after each stop of said device as a function of discharge of said energy storing means affords under given conditions automatic restarting.
- 45 2. In control for an electric motor driven traveling device, the combination with means to effect travel of the device through a plurality of zones, said means including a plurality of push button switches, at least one for each zone of travel served by the device, said push button switches being operable selectively to start said device and direct it to the corresponding zone, of separate condenser type energy storing means connected in circuit with said push button switches for charging of the former from an
- 50 3. In control for an electric motor driven traveling device, the combination with means to effect travel of the device through a plurality of zones, said means including a plurality of push button switches, at least one for each zone of travel served by the device, said push button switches being operable selectively to start said device and direct it to the corresponding zone, of separate condenser type energy storing means connected in circuit with said push button switches for charging of the former from an
- 55 4. In control for an electric motor driven traveling device, the combination with means to effect travel of the device through a plurality of zones, said means including a plurality of push button switches, at least one for each zone of travel served by the device, said push button switches being operable selectively to start said device and direct it to the corresponding zone, of separate condenser type energy storing means connected in circuit with said push button switches for charging of the former from an
- 60 5. In control for an electric motor driven traveling device, the combination with means to effect travel of the device through a plurality of zones, said means including a plurality of push button switches, at least one for each zone of travel served by the device, said push button switches being operable selectively to start said device and direct it to the corresponding zone, of separate condenser type energy storing means connected in circuit with said push button switches for charging of the former from an
- 65 6. In control for an electric motor driven traveling device, the combination with means to effect travel of the device through a plurality of zones, said means including a plurality of push button switches, at least one for each zone of travel served by the device, said push button switches being operable selectively to start said device and direct it to the corresponding zone, of separate condenser type energy storing means connected in circuit with said push button switches for charging of the former from an
- 70 7. In control for an electric motor driven traveling device, the combination with means to effect travel of the device through a plurality of zones, said means including a plurality of push button switches, at least one for each zone of travel served by the device, said push button switches being operable selectively to start said device and direct it to the corresponding zone, of separate condenser type energy storing means connected in circuit with said push button switches for charging of the former from an
- 75 8. In control for an electric motor driven traveling device, the combination with means to effect travel of the device through a plurality of zones, said means including a plurality of push button switches, at least one for each zone of travel served by the device, said push button switches being operable selectively to start said device and direct it to the corresponding zone, of separate condenser type energy storing means connected in circuit with said push button switches for charging of the former from an

energy source upon operation of said switches, electroresponsive means requiring energization for stopping said traveling device and responsive to discharge of any of said energy storing means, and means responsive to the movement of said traveling device to afford discharge of said separate storing means which have been charged, in a predetermined order irrespective of the order of actuation of said push button switches, when said device enters the respective zone, regardless of any temporary failure of the source of charging current, the first mentioned means comprising means which after each stop effected by said energy storing means affords restarting automatically until all calls registered by said push button switches are answered.

3. In control for an electric motor driven traveling device, the combination with means to effect travel of the device in either direction through a plurality of zones, said means including a plurality of push button switches, at least one for each zone of travel served by the device, said push button switches being operable selectively to start said device and direct it to the corresponding zone, of a plurality of condenser type energy storing means, means effective upon operation of one or more of said push button switches to store up electrical energy from an energy source in one or more of said energy storing means corresponding to the push button switch or switches operated, electroresponsive means requiring energization for stopping said traveling device and responsive to discharge of any of said energy storing means, and means responsive to the movement of said traveling device to afford discharge of said separate energy storing means which have been charged, in a predetermined order irrespective of the order of actuation of said push button switches, when said device enters the respective zone, regardless of temporary failure of the source of charging current, the first mentioned means including means affording automatic restarting and automatic reversals when needed to effect discharge of the charged condensers.

4. In a control for an electric motor driven traveling device, in combination, a reversible motor to effect movement of the traveling device into a plurality of zones of travel, electromagnetic control means for said motor affording starting thereof in opposite directions and including means requiring energization for stopping, a plurality of push button switches, at least one for each zone served by the device, said push button switches being operable selectively to effect starting of said device by said electromagnetic control means in reverse directions and directing said device to the corresponding zone, a plurality of condensers, means effective upon operation of any of said push button switches to store up electrical energy in one or more of said condensers corresponding to the push button switch or switches operated, a zone type selector driven by said motor to afford connections from said condensers selectively to said stopping means to discharge the condensers selected thereby which have been charged, said selector so rendering the charged condensers effective in a predetermined order irrespective of the order of actuation of said push button switches, and means including another condenser coordinated with the aforementioned condensers to effect automatic reversal of said device when needed to effect answering of all calls registered by said push button switches.

5. In a control for an electric motor driven traveling device, in combination, a reversible motor to effect movement of the traveling device into a plurality of zones of travel, electromagnetic control means for said motor affording starting thereof in opposite directions and including means requiring energization for stopping, a plurality of push button switches at least one for each zone served by the device, said push button switches being operable selectively to effect starting of said device by said electromagnetic control means in opposite directions and directing said device to the corresponding zone, a plurality of condensers, means effective upon operation of any of said push button switches to store up electrical energy in one or more of said condensers corresponding to the push button switch or switches operated, a zone type selector coupled to said motor to afford discharge of the energy stored in said condensers which have been charged to effect energization of said stopping means, said selector so rendering the charged condensers effective in a predetermined order irrespective of the order of actuation of said push button switches, and means including other energy storing means of the condenser type coordinated with the aforementioned condensers to provide for reversal of said device at each terminal zone automatically when one or more of the first mentioned condensers has earlier been charged and requires such reverse travel of said device to effect discharge thereof.

6. In a control for an electric motor driven traveling device, in combination, a reversible motor to effect movement of the traveling device into a plurality of zones of travel, electromagnetic control means for said motor affording starting thereof in opposite directions and including means requiring energization for stopping, a plurality of push button switches at least one for each zone served by the device, said push button switches being operable selectively to effect starting of said device by said electromagnetic control means in opposite directions and directing said device to the corresponding zone, a plurality of condensers individual to said zones, means effective upon operation of any of said push button switches to store up electrical energy in one or more of said condensers corresponding to the push button switch or switches operated, commutating means coupled to said motor and connected in circuit with said push button switches to selectively control said electromagnetic control means, means to insure against reversal of the direction of travel of the device prior to arrival thereof at the most remote zone in the initial direction of travel, and a zone type selector coupled to said motor to afford discharge of the energy stored in said condensers which have been charged to effect energization of said stopping means, said selector so rendering the charged condensers effective in a predetermined order irrespective of the order of actuation of said push button switches.

7. In a control for an electric motor driven traveling car, in combination, a reversible motor to effect movement of the car into a plurality of zones of travel, electromagnetic control means for said motor affording starting thereof in opposite directions, and including means requiring energization for stopping, a plurality of push button switches at least one for each zone served by the device, said push button switches being operable selectively to effect starting of said car by said electromagnetic control means in opposite

directions and directing said car to the corresponding zone, a plurality of condensers individual to said zones, means effective upon operation of any of said push button switches to store up electrical energy in one or more of said condensers corresponding to the push button switch or switches operated, commutating means coupled to said motor and connected in circuit with said push button switches to selectively control said electromagnetic control means, means to insure against reversal of the direction of travel of the car prior to arrival thereof at the most remote zone in the initial direction of travel, and a zone type selector coupled to said motor to afford discharge of the energy stored in said condensers which have been charged to effect energization of said stopping means, said selector so rendering the charged condensers effective in a predetermined order irrespective of the order of actuation of said push button switches, the effectiveness of said condensers which have been charged prior to a temporary failure of power of said means being unaffected by such temporary failure.

8. In a selective collective control system for an elevator or other reversible traveling device, characterized by storing of energy for registration of calls and also by discharge of stored energy for stopping the traveling device automatically as each call is met, the combination with condenser type energy storing means to so function, of reversing means for the traveling device comprising additional condenser type energy storing means which is dependent upon the former energy storing means for charge and which when charged effects operation of said reversing means, and means controlling said additional energy storing means automatically for charge thereof when but only when reversal of the traveling device is needed for response to a call registered by charge of the first mentioned energy storing means.

9. In a selective collective control system for an elevator or other reversible traveling device, characterized by storing of energy for registration of calls and also by discharge of stored energy for stopping the traveling device automatically as each call is met, the combination with condenser type energy storing means to so function, of reversing means for the traveling device comprising additional condenser type energy storing means which is dependent upon the former energy storing means for charge and which when charged effects operation of said reversing means, and means controlling said additional energy storing means automatically for charge thereof when but only when reversal of the traveling device is needed for response to a call registered by charge of the first mentioned energy storing means, said additional energy storing means discharging as an incident to reverse travel induced thereby, the energy stored therein to bring about the reversal.

10. In a selective collective control system for an elevator or other traveling device, characterized by storing of energy for registration of calls and also by discharge of stored energy for stopping of the traveling device automatically as each call is met, the combination with condenser type energy storing means to so function, of reversing means for the traveling device comprising additional condenser type energy storing means which when charged effects operation of said reversing means, and means controlling said additional energy storing means automatically for charge thereof when but only when reversal of the traveling device is needed for response to a

call registered by a charge of the first mentioned energy storing means.

11. In a selective collective control system for an elevator or other traveling device, characterized by storing of energy for registration of calls and also by discharge of stored energy for stopping of the traveling device automatically as each call is met, the combination with condenser type energy storing means to so function, of reversing means for the traveling device comprising additional condenser type energy storing means which when charged effects operation of said reversing means, and means controlling said additional energy storing means automatically for charge thereof when but only when reversal of the traveling device is needed for response to a call registered by a charge of the first mentioned energy storing means, said additional energy storing means discharging as an incident to reverse travel induced thereby, the energy stored therein to bring about the reversal.

12. In a selective collective control system for an elevator or other traveling device, characterized by storing of energy for registration of calls and also by discharge of stored energy for stopping of the traveling device automatically as each call is met, the combination with condenser type energy storing means to so function, of reversing means for the traveling device comprising a pair of condensers which are chargeable selectively to effect different operations of said reversing means selectively, and means controlling said pair of condensers automatically for charge of each when but only when the reversal to be effected thereby is needed for response to a call registered by a charge of the first mentioned energy storing means.

13. In a selective collective control system for an elevator or other traveling device, characterized by storing of energy for registration of calls and also by discharge of stored energy for stopping of the traveling device automatically as each call is met, the combination with condenser type energy storing means to so function, of reversing means for the traveling device comprising a pair of condensers which are chargeable selectively to effect different operations of said reversing means selectively, and means controlling said pair of condensers automatically for charge of each when but only when the reversal to be effected thereby is needed for response to a call registered by a charge of the first mentioned energy storing means, each of said pair of condensers discharging as an incident to the reverse travel induced thereby, thus to avoid interference with further reversal for response to all calls registered.

14. In a selective collective control system for an elevator or other reversible traveling device, the combination with reversing means for the traveling device comprising condenser type energy storing means through the medium of which operation of said reversing means may be prearranged, and means controlling said energy storing means automatically to so prearrange an operation of said reversing means when but only when reversal of the traveling device is required for response to a call registered.

15. In a selective collective control system for an elevator or other traveling device, characterized by storing energy for registration of calls and also by discharge of stored energy for stopping of the traveling device automatically as each call is met, the combination with energy storing means to so function, of reversing means for the

traveling device comprising additional energy storing means and also electronic means under the control of said additional energy storing means, said electronic means and its controlling energy storing means affording means by which an operation of said reversing means may be pre-arranged, and means controlling said additional energy storing means automatically for so pre-arranging an operation of said reversing means when but only when reversal of the traveling device is needed for response to a call registered by charge of the first mentioned energy storing means.

16. In a selective collective control system for an elevator or other reversible traveling device, characterized by means responsive for registration of calls and for stopping the traveling device automatically as each call is met, the combination with registering means to so function, of reversing means for the traveling device comprising condenser type energy storing means which is dependent upon said registering means for charge and which when charged effects operation of said reversing means, and means controlling said energy storing means automatically for charge thereof when but only when reversal of the traveling device is needed for response to a call registered by said registering means.

17. In a selective collective control system for an elevator or other reversible traveling device, characterized by means responsive for registration of calls and for stopping the traveling device automatically as each call is met, the combination with registering means to so function, of reversing means for the traveling device comprising condenser type energy storing means which is dependent upon said registering means for charge and which when charged effects operation of said reversing means, and means controlling said energy storing means automatically for charge thereof when but only when reversal of the traveling device is needed for response to a call registered by said registering means, said energy storing means discharging as an incident to reverse travel induced thereby, the energy stored therein to bring about the reversal.

18. In a selective collective control system for an elevator or other reversible traveling device, characterized by means responsive for registration of calls and for stopping the traveling device automatically as each call is met, the combination with registering means to so function, of reversing means for the traveling device comprising dual condenser type energy storing means which are chargeable selectively to effect different op-

erations of said reversing means selectively, and means controlling said dual energy storing means automatically for charge of each when but only when the reversal to be effected thereby is needed for response to a call registered by said registering means.

19. In a selective collective control system for an elevator or other reversible traveling device, characterized by means responsive for registration of calls and also for stopping the traveling device automatically as each call is met, the combination with registering means to so function, of reversing means for the traveling device comprising dual condenser type energy storing means which are chargeable selectively to effect different operations of said reversing means selectively, and means controlling said dual energy storing means automatically for charge of each when but only when the reversal to be effected thereby is needed for response to a call registered by said registering means, each of said dual energy storing means discharging as an incident to the reverse travel induced thereby, thus to avoid interference with further reversal for response to all calls registered.

20. In a selective collective control system for an elevator or other traveling device, characterized by means for registration of calls and also for stopping of the traveling device automatically as each call is met, the combination with registering means to so function, of reversing means for the traveling device comprising energy storing means and also electronic means under the control of said energy storing means, said electronic means and its controlling energy storing means affording means by which an operation of said reversing means may be prearranged, and means controlling said energy storing means automatically for so prearranging an operation of said reversing means when but only when reversal of the traveling device is needed for response to a call registered by charge of said registering means.
